Chicago, Ill., a corporation of Illinois
Filed June 23, 1961, Ser. No. 119,215
6 Claims. (Cl. 263—41)

This invention relates generally to gas fired furnaces, and more particularly, to vacuum furnaces.

In recent years there has been an increased demand for furnaces in which parts may be heated in a vacuum to high temperatures. There are a number of problems associated with heating of material in a vacuum which have not been satisfactorily solved by the prior art vacuum furnaces. Most of the prior art furnaces are unsuited to production applications in which the work charge must be heated quickly in a vacuum tight enclosure to a desired temperature and then cooled quickly prior to removal from the furnace.

It is conventional to employ radiation shields in connection with vacuum furnaces to concentrate the heat in the portion of the furnace containing the work charge. The necessity for a well sealed enclosure for the work charge as well as for radiation shields has produced furnaces which are difficult to load and unload. It would be desirable, therefore, to have a vacuum furnace in which the pressure tight enclosure may be easily opened and in which easy access may be had to the interior of the enclosure where the work charge is supported.

To withstand the high temperatures and pressures required in vacuum furnace applications, it is well known to use heavy walled retorts fabricated of alloys which retain their strength at high temperature. With the work charge enclosed in such a retort, the rapid heating of the work is more difficult than in a conventional furnace in which the heating means may radiate directly to the work. In some instances this problem has been solved by placing electrical heating elements within the retort in close proximity to the work. This solution has many drawbacks since it increases the size of the retort and complicates its structure considerably. In addition, such a solution would not be suitable for a gas fired furnace inasmuch as the gas burner could not be placed within the vacuum enclosure. It would be desirable, therefore, to have a furnace in which gas fired means are provided to heat rapidly a vacuum retort.

We have found that the rapid heating of the retort may best be accomplished by an arrangement in which combustion of the gas-air mixture takes place over a substantial area of the inner wall of the furnace adjacent the vacuum retort. While it is known in the art to pass a combustible gas through a refractory wall with combustion taking place along one wall surface, it has been necessary to provide elaborate sealing means to prevent leakage of gas through the refractory material to undesired areas. In addition, it has been necessary to form the refractory material in intricate shapes to assure proper combustion only on the inner wall and to assure proper cooling of the refractory material so combustion would not take place within or behind the wall. These problems encountered in the use of a porous wall type of gas burner have restricted its use considerably.

It is, therefore, an object of the present invention to provide an improved vacuum furnace.

It is a further object of the invention to provide a vacuum furnace having means for readily loading and removing the parts from the vacuum retort.

It is an additional object of the invention to provide a vacuum furnace having improved heating and cooling means whereby the vacuum retort of the furnace may be quickly heated and cooled.

2

It is a further object of the invention to provide a vacuum furnace having a simplified porous wall type of gas burner.

Further objects and advantages of the present invention will become apparent as the following description proceeds and the features of novelty which characterize the invention will be pointed out with particularity in the claims annexed to and forming a part of this specification.

For a better understanding of the present invention reference may be had to the accompanying drawings in which:

FIG. 1 is a sectional view in elevation of an improved vacuum furnace constructed according to the present invention;

FIG. 2 is a plan view of the furnace of FIG. 1 with a portion thereof shown in section; and

FIG. 3 is an enlarged view of the radiation shields employed in the furnace.

Briefly, the invention comprises a vacuum furnace including a vacuum-tight retort which is heated within an enclosure of refractory material, the combustion gases for the furnace passing through the porous walls of the refractory enclosure with combustion taking place on the inner wall face. Air cooling means are provided at the upper and lower limits of the side walls of the refractory enclosure, such cooling means preventing leakage of the combustible material from the porous walls of the enclosure and serving to maintain the walls at a temperature below the combustion temperature of the gas and to cool the furnace quickly at the end of the heat treating period. The vacuum retort comprises a cylindrical chamber closed at the top and having a removable closure positioned at the bottom opening thereof. The removable closure serves as a support for a fan and is movable downwardly from its position in sealing engagement with the opening in the retort to a position in which parts may be readily loaded thereon.

Referring now to the drawings, there is illustrated in FIGS. 1 and 2 of the drawings a furnace generally designated by the reference numeral 11. The furnace 11 comprises vertical supports 12 which serve to support an enclosure 13. The furnace enclosure 13 is formed in the conventional manner having an outer cylindrical compartment 14 formed of steel plate, which compartment surrounds a lining 15 of refractory material. The lining 15 may be made up of individual firebrick or preformed slab.

The lining 15 includes a roof or cover portion 16 which is substantially circular in shape having a central opening 16a formed therein for discharge or venting of flue gases. The refractory cover 16 is supported on one of three annular flanges 14a which extend around the interior of the circular compartment 14. Immediately below the refractory cover 16 there is a cylindrical refractory wall portion 17 which in a preferred embodiment was of six inches thick 2600 degrees insulating firebrick. The annular flanges 14a engage the wall portion 17 and support it within compartment 14. On the outer faces of the cylindrical refractory wall 17, there are formed a pair of peripherally extending passageways 17a which serve as combustion manifolds for the furnace. The annular passageways 17a are filled with rock wool designated by reference numeral 18. Because of the porous nature of the rock wool 18, it permits the air-gas mixture to pass through the annular manifolds 17a readily but is effective as a fire check in the event of a flash back through the porous walls of the furnace. The rock wool also acts as a filter for the incoming air-gas mixture.

Extending around the outside of the cylindrical compartment 14 adjacent the annular manifolds 17a are channel members 19 which are suitably welded to the cyl-

drical wall of the compartment 14 to form two sealed combustion manifolds 19a into which a mixture of gas and air is fed. A series of holes 14b are formed in the wall of compartment 14 permitting the combustible mixture to flow from the manifolds 19a formed by the channel members 19 into the passageways or manifolds 17a in the refractory wall 17. In the preferred embodiment, a total of sixteen $\frac{7}{16}$ inch diameter holes equally spaced around the periphery of the compartment 14 were provided to permit the flow of the combustible mixture into each of the manifolds 17a.

It should be understood that the porosity of the refractory material 17 permits the air-gas mixture to pass from the annular manifolds 17a through the walls to the inside of the refractory lining 15 at which point combustion of the air-gas mixture occurs. While the refractory material 17 is porous and permits the gas mixture to pass upwardly and downwardly as well as inwardly, means are provided to prevent the leakage of the gas mixture in directions other than toward the interior of the refractory lining 15. The upper and lower edges of the cylindrical refractory wall 17 are sealed at their joints with the adjoining refractory portions by an air setting cement. This cement prevents the passage of the air-gas mixture through these joints. Since it is virtually impossible to achieve a perfect gas seal with such sealing cement, additional means are provided to assure against the dangerous leakage of the air-gas mixture.

Immediately below the cylindrical wall 17 there is a bottom member 20 which completes the refractory lining 15. The bottom member 20 is annular in shape having a large opening 20a formed in the center thereof. The refractory member 20 is supported on an annular plate 21 which is part of the steel plate compartment 14. The bottom member 20 cooperates with the cylindrical wall 17 and the cover 16 to form the refractory furnace lining 15 into which a vacuum retort 23 is inserted upwardly through opening 20a. The retort 23, which is made of a suitable high temperature alloy which will maintain its strength at elevated temperatures, is generally cylindrical in shape having a closed upper end and an open lower end with a circular flange 23a secured thereto adjacent the lower end for supporting the retort with respect to the compartment 14.

Immediately above and below the channel members 19 which form combustion manifolds 19a, there are additional channel members 24 which are secured to compartment 14 in the same manner as channel members 19 and which form cooling manifolds 24a to conduct air to the upper and lower portions of the compartment 14. The refractory cover 16 is formed at its lower outer edge with an annular shouldered portion 16b which cooperates with the flange 14a and the outer wall of compartment 14 to form an annular passageway 22 within the refractory lining. A suitable fibrous, high temperature resistant material such as rock wool is placed in passageway 22 to filter in air passing therethrough. The rock wool also affords some thermal insulation during periods when no air is passed through the passageway 22. A plurality of holes 14c extend through the cylindrical wall of the steel plate compartment 14 to permit the passage of cooling air from the channel 24 into the passage 22. Similarly, at the lower end of the furnace, the bottom member 20 is formed at its upper outer edge with a shouldered portion 20b which cooperates with the compartment 14 and a flange 14a to form an annular passageway 31 therein. A plurality of holes 14d extend through the wall of the compartment 14 permitting air to flow from the lower channel member 24 into the passageway 31.

The air supplied to the upper and lower channels 24 not only serves to cool the furnace walls during operation of the furnace and at the termination of a heating cycle but also is important in preventing leakage of the combustion gases upwardly and downwardly through the cylindrical walls 17. Thus, by pressurizing the air in the

passageways 22, 31 to approximately the same pressure as the combustion gas mixture within the manifolds 17a, there is no tendency for the combustion gases to escape upwardly through the refractory cover 16 or downwardly through the refractory bottom member 20. The air flow in passageways 22 and 31 is maintained at a minimum to accomplish this pressurizing function. The gas mixture simply moves through the porous wall 17 to the inner surface thereof where combustion takes place. The combustion of the gas at the inner surface of the refractory lining 15 is substantially continuous across the cylindrical refractory wall 17 and heats the interior thereof rapidly and uniformly. The use of upper and lower manifolds 17a, 19a permits some adjustment in the heating rate to compensate for the higher losses and heat storage in the bottom part of the chamber.

To cool the furnace, suitable valves are provided whereby the gas may be shut off and air passed through the combustion manifolds 17a. The passage of such air through the refractory wall 17 results in extremely rapid and efficient cooling.

The rate of flow of the gas mixture through the porous walls 17 of the refractory lining cools the walls and prevents the walls from heating up to such a temperature that combustion might occur within the wall 17 or the combustion manifolds 17a. The air passageways 22, 31 serve to reduce the temperature of the furnace walls at the cover 16 and the bottom member 20. In that no air-gas mixture passes through the cover 16 or bottom member 20, there would be a tendency for the portions adjacent the cylindrical wall 17 to heat up to excessively high temperatures. High temperatures at these adjacent portions would create a possibility of flash backs through the upper and lower portions of cylindrical wall 17. It should be understood, therefore, that the air delivered to the passageways 22, 31 through the manifolds 24 serves the purposes of preventing leakage of the gas mixture upwardly or downwardly from the porous wall 17, of cooling the top and bottom of refractory wall 17 during operation, and of cooling the furnace down after the heating cycle is terminated.

To permit connection of a vacuum pump to the interior of the retort 23, there is provided at the lower end of the retort an opening 23b in the side wall thereof. A vacuum conduit 25 is connected to the retort 23 in communication with the opening 23b. The conduit 25 has at its outer end a pipe nipple 26 to which a suitable vacuum pump may be connected.

A sealing flange 27 is secured to the lower end of the retort 23 to facilitate the sealing thereof. The flange 27 has an annular groove 27a formed in the lower face thereof. The groove 27a is adapted to receive an O-ring sealing gasket 28 of silicone rubber or other high temperature resilient material. On the upper face of the sealing flange 27 there is mounted an inverted channel-shaped member 29 which cooperates with the flange 27 to form a water cooling passageway 30. Suitable water connections are provided to circulate cooling water through the passageway 30 to reduce the temperature of the sealing flange 27 and the gasket 28.

To seal the bottom opening of the retort 23 there is provided a closure member 32 which also supports a circulating fan 33. The closure member 32 is a large annular member having an opening 32a in the center thereof through which a fan shaft 33a extends. Mounted on the upper end of the fan shaft is an impeller member 33b. The fan is of conventional construction being adapted for high temperature application by the inclusion of separate water cooling means in the base thereof and having a sealed construction so that no air may enter through the motor portion of the fan 33. The primary purpose of the fan is to circulate a coolant gas at the end of the heat treating operation when the contents of the retort are to be cooled rapidly to a low temperature.

The closure member 32 not only supports the circulat-

ing fan 33, but also supports a plurality of radiation shields 34 which are positioned in the lower end of the retort 23. The purpose of the radiation shields 34 is to concentrate the heat in the upper high temperature portion of the retort 23 and limit heat transfer downwardly to the point at which the vacuum seal is made between the closure member 32 and the bottom opening in the retort. In addition, it is desirable to maintain the circulating fan 33 at as low a temperature as possible. The radiation shields 34 are supported in vertically spaced relation by means of six posts 35 which are equally spaced around a supporting flange 36. The flange 36 is secured to the retort closure member 32 by means of bolts or the like while the posts 35 are received in holes in the flange 36 and welded thereto.

As may best be seen in FIG. 3, the radiation shields 34 are formed with openings 34a through which the posts 35 extend. To maintain the shields vertically spaced with respect to one another, a plurality of cylindrical spacers 37 are received on the posts 35 and positioned between the shields 34. There is an upper set of shields 38 positioned above the impeller 33b and a lower set of shields 49 positioned below the impeller 33b. As may best be seen in FIG. 3, each set of radiation shields is carried by a horizontally disposed plate member 39 having a vertical boss 40 extending upwardly at the center thereof in alignment with a hole 39a in the plate member. While the diameter of the boss 40 in the upper set of shields 38 is larger than the diameter of the lower boss, the sets of radiation shields 38 and 49 are otherwise identical. Additional spacers 41 are received around the boss 40 and positioned between the radiation shields 34. The use of the spacers 37 and 41 engaging the radiation shields 34 over substantial areas permits the use of a very light stainless steel for the shield material which in one constructed embodiment was only 16 gauge. Without the multiple support provided by the plate 39 and the spacers 37 and 41, there would be a tendency for the shields to deform at the high temperatures to which they are subjected. The upper set of radiation shields 37 and the lower set 38 are vertically located on the posts 35 by means of cylindrical spacers 42 which are received on the posts 35 as may best be seen in FIG. 4.

To support parts which are to be heated, there is provided at the upper end of the posts 35 a platform 43 which is generally circular in shape and is horizontally disposed within the retort 23. The platform has a cylindrical skirt 44 which extends around the outer edge thereof and projects below the level of the platform about twice the distance that it extends above the platform 43. Secured to the lower face of the platform 43 and extending downwardly therefrom are six cylindrical pipe sections 45 which are received on the posts 35 and serve to space the platform 43 above the upper set of radiation shields 38. Secured to the pipe sections 45 and extending radially inwardly therefrom are webs 46 which support at their inner end a circular baffle member 47. The baffle member 47 is intended to prevent radiation downwardly through a center opening 43a in the platform 43. To support the work above the surface of the platform 43, there are a plurality of radially extending spacers 48 secured to the platform 43 and extending inwardly from the cylindrical skirt 44.

The closure member 32 along with fan 33 and the radiation shields 34 and platform 43 are supported for vertical movement by an elevator designated generally by reference numeral 50. The elevator 50 includes a carrier 51 to which the retort closure member 32 is bolted. The carrier 51 comprises a rectangular steel frame to which is secured vertically extending guide sleeves 52. The guide sleeves 52 are slidably received on two posts 53 which are secured at their upper ends to the compartment 14. To move the carrier 51 between two vertically spaced positions, there are provided a pair of air cylinders 54 which are located on diametrically opposed sides

of the furnace enclosure 13. The air cylinders are secured at their upper ends to compartment 14 and have their movable pistons connected to the carrier 51. Control means are provided to deliver air to the cylinders at a controlled rate whereby the carrier 51 may be moved from the position in which the closure member 32 is in sealing engagement with the retort 23 as shown in solid lines in FIG. 1 to the dotted position shown in FIG. 1, which may be considered the loading or unloading position. After the carrier 51 has been moved to the lowermost position, the platform 43 is easily accessible for loading or unloading parts.

In view of the detailed description included above, the operation of the vacuum furnace should be readily understood. The elevator and sealing mechanism associated with the closure member for the vacuum retort provides a simple and easily operated means for facilitating loading and unloading of the furnace. In addition, the burner arrangement utilizing the refractory walls or lining 17 results in a structurally simple means for heating or cooling the vacuum retort at a rapid rate.

While there has been illustrated and described only one form of the invention, it will be understood that numerous changes and modifications will occur to those skilled in the art and it is aimed in the appended claims to cover all such changes and modifications as fall within the true spirit and scope of the present invention.

What is claimed as new and desired to be secured by Letters Patent of the United States is:

30. 1. A vacuum furnace comprising a pressure-tight cylindrical retort supported with the axis thereof extending vertically and having a closed upper end and an open lower end, a closure plate for said retort carried by an elevator vertically movable between an upper position in sealing engagement with said open lower end and a lowered position, a plurality of vertically spaced, horizontally disposed radiation shields mounted on the upper surface of said closure plate, and a work supporting means carried by said closure plate and positioned above said radiation shields, said work supporting means being spaced below said retort when said elevator is in said lowered position.

45. 2. A vacuum furnace comprising an insulated enclosure having a bottom opening therein, a pressure-tight retort mounted in said enclosure with an open end extending downwardly through said opening, a closure plate for said retort carried by an elevator vertically movable between an upper position in sealing engagement with said open end of said retort and a lowered position, a fan supported on the bottom of said closure plate having an impeller mounted above said plate, radiation shields carried by said closure plate and positioned between said plate and said impeller, a work supporting platform supported by said closure plate and positioned above said impeller, said platform in said lowered position of said elevator being below said retort to permit the loading of parts thereon.

50. 3. A vacuum furnace comprising a pressure-tight retort having an enlarged loading opening in the bottom thereof, a closure plate for said opening carried by an elevator vertically movable between an upper position in sealing engagement with said opening and a lowered position, resilient sealing means positioned between said closure plate and said retort, water cooling conduits on said retort to maintain said seal at a low temperature, a plurality of spaced radiation shields carried by said closure plate and positioned to direct the heat in said retort to the upper portion thereof, and a work supporting means carried by said closure plate above said radiation shields, said work supporting means being spaced below said retort when said elevator is in said lowered position.

65. 4. A vacuum furnace comprising an insulated enclosure of refractory material, a pressure tight cylindrical retort rigidly mounted within said enclosure with the axis thereof extending vertically and having a closed upper end and an open lower end, said enclosure being provided with

an opening through which the lower end of said retort extends, a closure plate for said retort carried by an elevator vertically movable between an upper position in sealing engagement with said lower end and a lowered position, an air circulation fan carried by said closure plate including a motor mounted below said plate and an impeller extending above said plate for insertion into said retort, gas manifold means for conducting an air-gas mixture to the outer walls of said refractory enclosure, said material being porous with passageways extending therethrough for said mixture to enter said enclosure for combustion on the inner wall thereof to heat said pressure tight retort, air manifolds for conducting air to the walls of said enclosure on either side of the wall areas receiving said air-gas mixture, said air conducted to said refractory walls pressurizing the passageways in said refractory wall surrounding said wall areas and preventing leakage of said air-gas mixture.

5. A gas fired furnace comprising a box-like enclosure of nonporous plate material, a pressure tight retort rigidly mounted within said enclosure and having a portion extending outwardly through an opening in the bottom thereof, said outwardly extending portion of said retort having an open lower end through which work to be heat treated may be inserted, a closure plate for said retort carried by an elevator vertically movable between an upper position in sealing engagement with said lower end and a lowered position, an insulating porous refractory lining for said enclosure spaced from the walls of said retort, manifolds formed between said nonporous enclosure and said refractory lining, supply means for delivering an air-gas mixture under pressure to said manifolds whereby said mixture passes through said porous lining for combustion at the inner face thereof, air manifolds positioned

10
15

adjacent said first-mentioned manifold between said nonporous enclosure and said refractory lining, and supply means for delivering air under pressure to said air manifolds, said air delivered by said air manifolds restricting passage of said air-gas mixture through said lining to a selected area.

6. The gas fired furnace of claim 5 including work supporting means carried by said closure plate, a plurality of vertically spaced horizontally disposed radiation shields positioned between said work supporting means and said closure plate, said work supporting means being spaced below said retort when said elevator is in said lowered position.
